UNITED STATES PATENT OFFICE.

HAROLD CEACLE POTTER, OF SHREVEPORT, LOUISIANA.

MIXING DEVICE FOR INTERNAL-COMBUSTION ENGINES.

1,396,054.

Specification of Letters Patent.

Patented Nov. 8, 1921.

Application filed January 31, 1921. Serial No. 441,299.

To all whom it may concern:

Be it known that I, HAROLD C. POTTER, a citizen of the United States, residing at Shreveport, in the parish of Caddo and

5 State of Louisiana, have invented a new and useful Mixing Device for Internal-Combustion Engines, of which the following is a specification.

This invention relates to mixers designed 10 for use in connection with internal combustion engines for breaking up the incoming gas to insure a rich mixture.

A further object of the invention is to provide a device of this character which 15 may be positioned within the intake manifold of an engine, at a point between the carbureter and engine cylinders so that the device will contact with the gas when the same has left the carbureter.

20 A still further object of the invention is to provide a mixer of a novel construction, whereby the same will be held within the intake manifold by frictional contact with the inner walls thereof, thereby eliminating 25 the use of bolts and other securing means.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without 35 departing from the spirit of the invention.

Referring to the drawing:—

Figure 1 illustrates a side elevational view of a blank of which the mixer is formed.

Fig. 2 illustrates a side elevational view 40 of the same, showing the fingers as twisted.

Fig. 3 illustrates a sectional view through the blank after the same has been bent to be positioned within a manifold, the relatively short fingers being shown as removed.

45 Fig. 4 illustrates a sectional view through the mixer showing the relation of the relatively short fingers with each other, the larger fingers having been removed.

Fig. 5 illustrates a sectional view disclosing 50 the relation of the short fingers with the long fingers, certain fingers being removed.

Fig. 6 illustrates a sectional view through 55 a manifold showing the mixer as supported therein.

Referring to the drawing in detail, the reference character 5 designates the body portion of the mixer, which is formed preferably of spring steel, portions thereof being cut away to provide a plurality of relatively short fingers 6, the upper ends thereof being cut at angles as indicated at 7, so that a space will be formed between the adjacent finger ends when the body portion is bent in a manner to be positioned within the mani- 60 fold. 65

Disposed between the relatively short fingers 6 are the longer fingers 8 which are supported in spaced relation with the relatively short fingers and have their free ends 70 cut at angles as at 9, thereby providing an opening at the adjacent ends of the fingers.

As shown, by Fig. 2 of the drawing, the fingers 6 are twisted to insure the gas passing over the fingers taking a spiral course 75 and imparting a swirling motion to the gas to cause the particles of oil forming a part of the mixture to be broken up into a fine spray.

The relatively long fingers 8 are also convoluted to give the charge a swirling motion, it being understood that the gas passes from the relatively short fingers 6, to the longer fingers 8 on its passage to the cylinders of the engine. 80

As before stated, the body portion 5 is formed preferably of spring steel, so that when the device is positioned within a manifold of an engine, the spring steel will expand and cause a frictional engagement 90 with the inner walls of the manifold, to the end that the device will be secured therein, and prevented from moving with respect thereto.

It is obvious that when the body portion 95 5 is bent to conform to the curvature of a manifold, the free ends of the relatively long fingers 8 move into close proximity to each other and provide a suitable opening to allow the gas to pass therethrough, while the relatively short fingers 6 have the free ends thereof in close proximity at points between the relatively large fingers, to insure the mixture contacting with the relatively short fingers on its passage through the mix- 100 105 ture.

In view of the foregoing description, it is believed that a further detail description of the operation of the device is unnecessary.

Having thus described the invention, what is claimed as new is:—

1. In a mixing device, a body portion formed of flexible material, said body portion adapted to be bent so that the ends thereof will overlap, the body portion adapted to frictionally engage the walls of a manifold pipe, and convoluted fingers forming a part of the body portion and adapted to be moved into close proximity with each other.

2. In a mixing device, in combination with an intake manifold, a body portion of flexible material and adapted to be bent to conform to the curvature of the manifold, said flexible material adapted to expand to frictionally engage the walls of the manifold, and convoluted fingers extending from one edge of the body portion and having

their free ends disposed in close proximity with each other.

3. In a mixing device, a body portion, a plurality of relatively short fingers extending from the body portion, relatively long fingers disposed between the first mentioned fingers and supported in spaced relation therewith, the free ends of the fingers being cut at angles, and said fingers adapted to lie in close proximity with each other when the device is positioned.

In testimony that I claim the foregoing as my own, I have hereto affixed my signature in the presence of two witnesses.

HAROLD CEACLE POTTER.

Witnesses:

M. T. HASSSLER,
W. P. HALL.
